UNITED STATES PATENT OFFICE.

JÓZEF PROTASIAK, OF MILWAUKEE, WISCONSIN.

AUTOMOBILE-SIGNAL.

1,254,730.

Specification of Letters Patent.

Patented Jan. 29, 1918.

Application filed February 5, 1917. Serial No. 146,822.

To all whom it may concern:

Be it known that I, JÓZEF PROTASIAK, a subject of the Czar of Russia, residing at Milwaukee, in the county of Milwaukee and State of Wisconsin, have invented certain new and useful Improvements in Automobile-Signals, of which the following is a specification.

This invention relates to automobiles and other like vehicles and has special reference to a signal for use in connection with vehicles to indicate the direction in which the vehicle is about to turn.

One object of the invention is to improve the general construction of devices of this character.

A second important object of the invention is to provide an improved device of this character wherein a signal lamp will be employed in connection with a swinging arm the lamp being housed within the arm when the signal is not being used and displayed externally of the arm when it is desired to give a signal.

A third important object of the invention is to provide an improved signal of this description wherein movement of a swinging arm will simultaneously permit movement of a signal lamp relative to the arm and at the same time effect the closing of a circuit through such lamp.

A fourth important object of the invention is to provide an improved signal including a tubular swinging arm and a signal lamp hinged to the arm and so arranged that when the arm is swung in one position the lamp will be displayed and when the arm is swung in a second position the lamp will be housed within said arm.

With the above and other objects in view, as will be hereinafter apparent the invention consists in general of certain novel details of construction and combinations of parts hereinafter fully described, illustrated in the accompanying drawing, and specifically claimed.

In the accompanying drawing, like characters of reference indicate like parts in the several views, and:

Figure 1 is a plan view of a small portion of an automobile body showing the device applied thereto.

Fig. 2 is a side elevation of the device as

shown in Fig. 1 but having certain of the parts in section in order to better disclose the construction.

Fig. 3 is a plan view showing the arm in its active position, certain of the parts being shown in section.

Fig. 4 is a rear elevation partly in section showing the arm swung out and the signal displayed.

Fig. 5 is a section on the line 5-5 of Fig. 4.

Fig. 6 is a section on the line 6-6 of Fig. 4.

Fig. 7 is a section on the line 7-7 of Fig. 4 looking in the opposite direction to Fig. 6.

In carrying out the objects of the invention there is disclosed a portion 10 of an automobile body and mounted on the side of this body is a bracket 11 having at its upper end a projecting arm 12. Journalized by means of a shaft 13 on the arm 12 is a hollow frusto-conical arm 14 having a flaring mouth portion 15.

Journalized in the bracket 11 is a shaft 16 carrying on its inner end a finger grip 17 the shaft extending through the side of the body 10. Furthermore, fixed on this shaft 16 is a gear 18 which meshes with a gear 19 fixed on a hollow stub shaft 20 carried by the tubular arm 14 and in alignment with the shaft 13. It will now be obvious that when the finger grip 17 is turned the gear 18 will cause rotation of the gear 19 and thus swing the arm 14 toward or from the body 10 as the case may be. In order to limit the extent of this swinging movement and to hold the device against accidental swinging movement there is provided on the back of the gear 18 a plate 21 having depressions or notches 22 formed therein. On the bracket 11 is carried a pair of spring fingers 23 the ends of which engage in certain of the notches 22 when the device is in the position shown in Fig. 1 and in the remaining notches when the device is in the position shown in Fig. 3. Thus these spring fingers 23 releasably lock the device in one position or the other as the case may be.

Hinged to one side of the mouth 15 is a signal disk consisting of a ring 24 carrying a plate glass closure 25 and a reflector 26 wherein is mounted an electric bulb 27.

Spaced ears 28 are fixed centrally to the back of the reflector 26 and pivoted to these ears is a push rod 29 which passes through a bearing 30 in the tubular arm 14. On 5 this push rod 29 is a collar 31 and between the collar 31 and the bearing 30 is a compression spring 32 which normally urges the push rod outward so as to cause the lamp and signal disk to assume the position 10 shown in Figs. 3 and 4. In order to retract the rod 29 when the lamp is swung in toward the side of the car there is provided a drum 33 which is fixed on the shaft 16 and connected to this drum is a flexible cord 15 or strand 34 which passes through the hollow shaft 20 and around an idler pulley 35 mounted in the arm 14, the end of the strand being connected to an eye 36 formed on the inner end of the rod 29. The arrangement 20 of the parts is such that as the shaft 16 is rotated the drum will be rotated and either pull upon the strand 34 or relax the tension on the strand. If the tension be relaxed the spring 32 will, of course, push the rod 29 25 outward and cause the parts to assume the position shown in Fig. 3. Meanwhile it must be remembered that the action of the gears will have effected the swinging of the arm 14 outward at right angles to the 30 body 10.

In order to provide for an electrical connection between the wires 37 which lead from a battery (not shown) and the lamp 27 the wires 37 extend through a cup-shaped 35 portion 38 of the bracket and thence through a bushing 39 which carries contact members 40 each of which is connected to a respective wire 37. This bushing 39 is normally urged outward by means of a spring 40 41 in the cup-shaped portion 38 and the contact members are arranged to engage similar contact members 42 mounted on the end of the horn opposite the lamp so that from these contact members 42 wires 43 may 45 be led to the lamp 27. Thus when the parts are in the position shown in Fig. 1 the contact members 40 and 42 would be separated and no current will flow through the lamp. Similarly when the parts are in the position 50 shown in Fig. 3 these contact members will be engaged and current will flow through the lamp. It will be obvious that a suitable switch may be provided to disconnect the wires 37 from the battery so that in 55 day time current may not be consumed but simply the signal ring 24, which is preferably white or some other conspicuous color, may be used for the signal.

In order to protect the device when in the position shown in Figs. 1 and 2 a guard 60 bracket 44 may be mounted on the body 10 as clearly shown in these figures.

In the operation of the device in general when the operator desires to turn to one direction or the other he manipulates the 65 finger piece 17 on the side of the car in the direction in which he desires to turn it being understood that one of these devices is used on each side of the car by preference. When this is done the arm is moved from 70 the position shown in Fig. 1 to that shown in Fig. 3 and at the same time the signal disk and lamp are swung outward as also shown in said figure. Simultaneous with this operation the circuit is closed and the lamp lighted provided the switch between the battery and wires 27 is closed. When the automobile has completed its turning movement a reverse movement of the finger grip will 75 restore the parts to the position in Fig. 1. 80

There has thus been provided a simple and efficient device of the kind described and for the purpose specified.

It is obvious that many minor changes may be made in the form and construction 85 of the invention without departing from the material principles thereof. It is not therefore desired to confine the invention to the exact form herein shown and described but it is wished to include all such as properly 90 come within the scope claimed.

Having thus described the invention, what is claimed as new, is:—

In a device of the kind described, a bracket, a shaft journaled in said bracket, 95 a finger piece on the shaft, a second shaft journaled in the bracket, a hollow arm on the second shaft, a gear fixedly connected to the hollow arm, a gear fixed on the first shaft and meshing with the first-mentioned gear, a drum fixed on the first shaft, a signal hinged at one side to one side of the free end of the hollow arm and movable into and out of the arm, a push rod in the hollow arm and having one end pivotally connected to the signal in spaced relation to the hinge thereof, a spring normally urging said push rod outward, and a flexible strand wound around said drum and having one end connected to the push rod. 100 105

In testimony whereof I have affixed my signature:

JÓZEF PROTASIAK.
